UNITED STATES PATENT OFFICE.

JOSEPH HENDERSON STEWART, OF BLUFF CITY, TENNESSEE.

TIE.

No. 915,244.

Specification of Letters Patent. Patented March 16, 1909.

Application filed February 25, 1907, Serial No. 359,086. Renewed February 9, 1909. Serial No. 477,021.

To all whom it may concern:

Be it known that I, JOSEPH H. STEWART, a citizen of the United States, residing at Bluff City, in the county of Sullivan and State of Tennessee, have invented a new and useful Improvement in Ties, of which the following is a specification.

This invention relates to ties and more particularly to a metallic tie, the object 10 being to provide a tie which is very simple and cheap in construction and one which will be securely held in place without any danger of it moving.

Another object of my invention is to provide the tie with clamping members which can be swung up or out of the way when it is desired to place a new rail thereon.

Another object of my invention is to provide very simple locking means for the 20 clamping member so that the member can be moved so as to aline with the rails.

With these and other objects in view, the invention consists in the novel features of construction, combination and arrangement 25 of parts hereinafter fully described and pointed out in the claims.

In the drawings forming a part of this specification:—Figure 1 is a top plan view of my improved tie showing the rails secured 30 thereon. Fig. 2 is a longitudinal sectional view through the tie. Fig. 3 is a top plan view of a portion of a tie. Fig. 4 is a perspective view of one of the coupling members. Fig. 5 is a perspective view of one of 35 the locking pins.

In the drawings A indicates a metal trough-shaped tie provided with opened ends, the vertical walls of which are connected together at their ends by strips A' 40 and the bottom of the tie is provided with transverse ribs to prevent the tie from moving when embedded in the ground. Notches A² are formed in the side walls of the tie, adjacent each end in alinement with partitions A³ formed in the tie, adjacent each end on which the rails B are adapted to rest.

Transverse openings are formed in the sides of the tie adjacent each end, in which are secured bolts C on which are pivotally 50 mounted clamping members D having elongated openings so that the members can move back and forth for the purpose hereinafter fully described. Tongues D' are formed on the members D adapted to fit over 55 the base of the rails and up against the web forming a brace for the rail. The outer ends

of the member D are rounded so that they can be swung upwardly so that the rail can be placed on the tie. The sides of the tie are provided with slots in alinement with 60 slots formed in the members D through which tapering pins E are adapted to pass so that the block can be adjusted and the track alined. The ends of the pins are reduced and threaded on which nuts are adapt- 65 ed to work, so as to securely lock the pins in place.

Clamping members F provided with elongated openings, are mounted on bolts G extending transverse through the walls of 70 the tie, on the inside of the rails, which are also provided with rounded ends so that they can be readily swung upwardly. Tongues F' are formed on the member F, adapted to fit over the base of the inside of the rail. Slots 75 are formed in the members F in alinement with slots formed in the walls of the tie, through which tapering pins H are adapted to pass, and be secured by nuts working on reduced threaded ends of the pins. It will be 80 readily seen that these members can be readily swung upwardly so that the rails can be placed therein and that the block can be readily clamped up against the rail, and alined by the tapering pins, so that the rails 85 will be readily fastened on the tie.

Having thus fully described my invention, what I claim as new and desire to secure by Letters Patent is:—

1. The combination with a trough-shaped 90 metal tie, of clamping members pivotally and slidably mounted in said tie, and means for adjusting said members.

2. The combination with a trough-shaped tie provided with notched walls, of clamping 95 members pivotally and slidably mounted between said walls at each side of said notches and means for adjusting and locking said members.

3. The combination with a trough-shaped 100 tie, provided with notched walls, of partitions formed in said ties, in alinement with said notches, clamping members pivotally and slidably mounted between said walls of the tie, at each side of the partitions and 105 means for locking and adjusting said member.

4. The combination with a trough-shaped tie, of clamping members provided with tongues pivotally and slidably mounted in 110 said tie, and wedge-shaped pins adapted to pass through said members for locking and adjusting said members.

5. The combination with a trough-shaped tie, provided with notches adjacent each end, of partitions formed in said tie in alinement with said notches, clamping members provided with transverse openings pivotally and slidably mounted in said tie, and wedge-shaped pins adapted to extend through said ties and clamping members.

6. The combination with a trough-shaped tie, provided with partitions adjacent each end and having slots formed in the sides, of

clamping members pivotally mounted in said tie, at each side of said partitions provided with slots, in alinement with the slots of the tie, and tapering pins adapted to extend through said slots for locking and adjusting said members. 15

JOSEPH HENDERSON STEWART.
